UNITED STATES PATENT OFFICE.

GEORGE WILLIAM COOPER, OF HANSBORO, NORTH DAKOTA.

GAME-BOARD.

1,127,594.

Specification of Letters Patent.

Patented Feb. 9, 1915.

Application filed February 12, 1914. Serial No. 818,338.

To all whom it may concern:

Be it known that I, GEORGE W. COOPER, a citizen of the United States, residing at Hansboro, in the county of Towner and State of North Dakota, have invented a new and useful Game-Board, of which the following is a specification.

This invention has reference to improvements in game boards, and more particularly game boards designed for the playing of the games known as chess and checkers, and its object is to provide an enlarged or magnified game board upon which the games may be played but which will be visible to a large number of observers.

Game boards of the character to which this invention relates are customarily of a size to rest upon the laps of two players sitting close together and facing each other, or to rest upon a table on opposite sides of which the players may be seated and readily reach to all parts of the board. The present invention contemplates the use of a game board of greatly magnified proportions, many times the size of the customary boards of like character, and, moreover, is so constructed as to be readily hung upon a wall so as to lie substantially flat thereagainst, and which when not in use may be lodged in a suitable protecting casing, for which reason the game board is made of flexible material, and may be applied to a spring or other roller lodged in the casing in a manner to permit the board to be withdrawn from the casing to its full length without being detached from the roller, and where a spring roller is employed, be drawn into the casing by the tension of the spring caused by the drawing out of the board from the casing. Because of the arrangement and character of the game board it is necessary to make provision for holding the chess men or checkers to the board, and also to provide magnified devices for the playing of the game, wherefore the game board appropriately divided off into proper spaces has each space and each man or playing element provided with coacting means for holding the men to the board allowing ready attachment or removal of the men and their change from place to place, and still not interfering with the rolling up of the board upon the roller in the casing. To facilitate the placing of the men upon the board and their removal therefrom, a manipulating device is provided since the board may be

so large that many of the spaces are out of reach of the players, and, moreover, in order that the board may be visible to an assembled audience of considerable size it must be placed high enough to be readily seen and must be of sufficiently large dimensions.

The invention will be best understood from a consideration of the following detailed description, taken in connection with the accompanying drawings forming a part of this specification, with the further understanding that while the drawings show a practical form of the invention, the latter is not confined to any strict conformity with the showing of the drawings, but may be changed and modified so long as such changes and modifications mark no material departure from the salient features of the invention.

In the drawings:—Figure 1 is an elevation of the improved game board, together with the casing designed to receive it, the board being shown in operative position, and both the casing and board being partly broken away to show otherwise hidden structure, a set of chess men also being shown applied to reserve spaces of the board. Fig. 2 is a vertical cross section of the structure of Fig. 1 drawn on a somewhat larger scale, but omitting the chess men. Fig. 3 is a section similar to that of Fig. 2, but showing the board in the rolled up position. Fig. 4 is a detail section on a larger scale than Figs. 1, 2 and 3, showing the manner of holding a playing element on the board. Fig. 5 is a perspective view of one of the playing elements. Fig. 6 is a longitudinal section of a manipulating tool designed for placing the men upon and removing them from the board. Fig. 7 is a perspective view of another type of playing element.

In referring to the structure of the present invention as a game board, although the playing indicia may be produced upon a flexible sheet, the term is employed in the general sense of a structure adapted to the playing of games customarily played upon stiff or rigid structures called game boards.

In accordance with the present invention there is provided a sheet which may be made of cloth or other suitable flexible material, or at least constructed so that it may be rolled up, but this does not preclude the use of stiff material where the storage of

the device in small compass is not material, but when the structure is to be transported from place to place the capability of being rolled up into a small compass is of value.

5 Upon the sheet 1 an appropriate area inclosed by a border 2 has produced thereover series of squares 3, 4, alternately light and dark, after the manner of an ordinary chess board, and, as is customary, the total number of squares is sixty-four. The sheet 1 is made considerably wider than the width of the area inclosed by the border 2 to provide storage spaces 5 so that the playing space is flanked on opposite sides by the storage 10 spaces 5. One edge, constituting the free edge of the curtain-like board, is formed with a hem 6 inclosing a rod 7, which may be of metal to serve as a weight for holding the curtain-like board 1 when in playing position pendent. The other end of the curtain-like board is made fast to a roller 8 which may be and preferably is a spring roller like those ordinarily employed for window shades or maps and the like. The 15 ends of the roller 8 are mounted in brackets 9 in turn secured in an elongated box or casing 10 of sufficient length and cross section to house the roller with the board rolled thereon as shown in Fig. 3. This 20 box is provided with suspending means which may be in the form of eyes 11 to engage over hooks 12 to be secured in any suitable support, such as a wall 13. One long side of the box or case 10 is in the form 25 of a door 14 connected to the body of the box by hinges 15, and at the free end provided with eyes 16 which may be engaged by hooks 17 carried on that portion of the box which, because of its position, may be termed 30 the front of the box, the construction being such that when the box or casing is hung on a wall by the hooks 12 the door 14 when released will fall pendent and then by grasping the hem portion 6 of the curtain-like board the latter may be withdrawn 35 from the casing to the desired extent to fully display the playing portion of the board, the rod 7 holding the board pendent and the spring of the spring roller being 40 put under superior tension sufficient to draw the curtain again into the casing when so desired, whereby the curtain is protected 45 from harm and is housed in a small compass facilitating transportation.

50 In each square 3 and 4 near the upper end thereof, considering the board as in playing position, there is formed a hole or passage 18 reinforced by an eyelet or gromet 19, although the presence of the gromet is not 55 necessary when the passage is otherwise protected against wear, as when the material employed for the curtain or board is such that the gromet is not needed. The storage spaces 5 are also provided with suitable 60 passages 20 which may be protected by eye-

lets or gromets 21 like the main or playing portion of the board. The storage spaces need only be sufficiently extensive to receive chess men 22, 23, the chess men 22 being distinguished from the chess men 23 usually by 70 difference in color or shading. For ordinary playing the chess men may be made of flat pieces of wood or other suitable material cut into appropriate outline and suitably marked or ornamented to represent the 75 proper characters, those shown consisting of king, queen, bishop, knight, rook, and pawns. It will be understood, however, that more elaborate devices may be employed for the men as may be desired, and 80 as the game of chess may be considered as in the nature of a battle, the pawns may be represented as soldiers, the knights as armored figures mounted on horses, the bishops may be represented with full robes and 85 miters, and the king and queen may be represented as clothed in regal robes.

Along the border 2 at the top and bottom of the checkered space laid off into the squares 3 and 4, appropriate words may be 90 produced and in the drawings these words consist of King and Queen, K. Bishop, Q. Bishop, K. Knight, Q. Knight, K. Rook and Q. Rook, while the upright or side lines of the border 2 have the numbers 1 to 8 opposite respective squares, those on one side reading from above downwardly, and those on the other side from below upwardly. 95

Each playing device is provided with a hook 24 projecting from the rear face near the upper end so as to be readily passed through the perforation 18 to suspend the playing device in suitable covering relation to the respective squares 3 or 4, as the case may be.

In order to facilitate the use of the structure, a manipulating tool is desirable, and such a tool is shown in Fig. 6 as consisting of a hollow rod 25 having one end formed into a relatively fixed jaw 26 and in operative relation thereto is another jaw 27 mounted on the rod by a pivot or hinge joint 28, a spring 29 serving to hold the jaw 27 in the closed position. At that end of the rod 25 remote from the jaw 26 a hand lever 30 is mounted on the rod by means of a hinge or pivot support 31, and this hand lever is normally constrained to one position by a spring 32 interposed between it and the rod 25. Within the rod are direction-changing pulleys 33, 34, respectively, and through the walls of the rod are perforations 35, 36, respectively. A cord 37 has one end made fast to an appropriate end of the lever 30 and from thence is passed through the perforation 36, about the pulley 34, thence lengthwise of the hollow rod to and about the pulley 33, thence out through the perforation 35, and is made fast to the corresponding end of the pivoted jaw 27.

Now by grasping the rod 25 so as to at the same time grasp the lever 30 on the spring side of the pivot 31, a pressure upon the lever will cause the compression of the spring 5 32 and a movement of the cord 37 in a direction to draw the corresponding end of the jaw 27 toward the rod against the action of the spring 29, thereby moving the other end of the jaw away from the jaw 26 10 and in this position any desired one of the men 22 or 23 are readily engaged as it hangs by the hook 24. Then by releasing the lever 30 the springs return the parts toward their first position, firmly grasping the particular man engaged, and this man may be removed from the board and moved to any other part of the board desired, the hook 24 being inserted through a suitable perforation 18, after which by a proper manipulation of the lever 30 the jaw 27 is moved 15 away from clamping engagement with the men and the latter is released.

The foregoing description has to do with a game of chess, while the game of checkers 25 simply requires a difference in the shape of the men, it being customary to play checkers with round or disk-like men, of which one is shown at 22^a in Fig. 7 rather than the more elaborately shaped ones employed 30 in the game of chess.

With the board of the present invention the progress of the game may be watched by many people. For smaller auditoriums the squares may be about six inches on each 35 side, making the playing part of the board four feet square, while for large auditoriums the squares 3 and 4 may be correspondingly larger, and it will be understood that the men or other playing devices 40 are made on a correspondingly magnified scale so that each man sufficiently covers a respective square, but should not be so large as to encroach on any adjoining square.

The invention, while not of necessity restricted to any particular size, is designed 45 for the playing of games upon a magnified or exaggerated scale, so as to be readily visible to many observers at one time, and the larger the gathering place for the observers 50 the larger should be the game board.

The particular colors or shades employed are not material, except that the men when made of flat form should be distinctly visible upon the respective squares.

55 What is claimed is:—

1. Means for playing games comprising a curtain-like game board, and playing devices adapted thereto, said playing devices and board having coacting means for sustaining the playing devices on the board, and the sustaining means on the board being substantially flush therewith to permit close rolling of said board on itself into compact form, whereby the curtain may be rolled up 60 65 without interference from projecting parts.

2. Means for playing games, comprising a curtain like game board of magnified or exaggerated size, and playing devices of corresponding size adapted to said board, the board being provided with a roller, and means for sustaining the roller with the game board in pendent position, said playing devices and board having coacting means for sustaining the playing devices on the board and the sustaining means on the board being constructed to permit rolling of the latter upon the roller into compact form.

3. Means for playing games, comprising a curtain-like game board with playing spaces produced thereon and the curtain within each space having a perforation therethrough, and playing devices adapted to the board and each provided with a projecting member adapted to extend through any one of the perforations to sustain the playing devices upon the board in proper relation to the playing spaces.

4. Means for playing games, comprising a curtain-like game board with playing spaces produced thereon and the curtain within each space having a perforation therethrough, and playing devices adapted to the board and each provided with a projecting member adapted to extend through any one of the perforations to sustain the playing devices upon the board in proper relation to the playing spaces, said board having reinforcing means at each perforation substantially flush with the surfaces of the curtain.

5. Means for playing games comprising a curtain-like game board adapted to be hung against a wall, the game board having playing spaces produced thereon and the playing means including playing devices adapted to the playing spaces on the board, and the latter being provided with storage spaces for the playing devices on opposite sides of the playing spaces.

6. Means for playing games comprising a curtain-like game board adapted to be hung against a wall, the game board having playing spaces produced thereon and the playing means including playing devices adapted to the playing spaces on the board, and the latter being provided with storage spaces for the playing devices on opposite sides of the playing spaces, said playing devices and the game board both within the playing spaces and the storage spaces having coacting means for sustaining the playing devices on the playing board in readily removable relation thereto and the sustaining means on the body of curtain and on the storage spaces being substantially flush with the faces of the curtain to provide for the close rolling of the curtain.

7. Means for playing games comprising a curtain-like game board adapted to be hung

4
against a wall, the game board having playing spaces produced thereon and the playing means including playing devices adapted to the playing spaces on the board, and the 5 latter being provided with storage spaces for the playing devices on opposite sides of the playing spaces, said playing devices and the game board both within the playing spaces and the storage spaces having coacting 10 means for sustaining the playing devices on the playing board in readily removable relation thereto, the portions of the coacting means upon the board being in substantially the plane thereof to permit rolling of the 15 board upon itself into compact form, and those portions of the sustaining means upon each playing device projecting therefrom on the face remote from the observed face.

8. A game board structure comprising a 20 roller, a casing in which the roller is mounted, a curtain-like game board secured at one edge to the roller and adapted to be rolled thereon to be inclosed by the casing, said game board having playing spaces produced 25 thereon and storage spaces on opposite sides of the playing spaces, the game board at the playing spaces and at the storage spaces having perforations, and playing devices adapted to the game board and each provided with 30 a sustaining member adapted to be passed through any one of the perforations on the game board.

9. A game board structure comprising a roller, a casing in which the roller is mounted, a curtain-like game board secured at one edge to the roller and adapted to be rolled thereon to be inclosed by the casing, said game board having playing spaces produced thereon and storage spaces on opposite sides 40 of the playing spaces, the game board at the playing spaces and at the storage spaces having perforations, and playing devices adapted to the game board and each provided with a sustaining member adapted to be 45 passed through any one of the perforations of the game board, the perforations of the game board being provided with reinforcements and the sustaining means on the playing devices being in the form of hooks 50 adapted to the reinforced perforations.

10. A game board structure comprising a curtain-like game board with playing spaces produced thereon, each space having a perforation near one edge, and playing devices 55 each having a sustaining member near one edge and adapted to any one of the perforations of the playing board to sustain the

playing devices in substantially centralized relation to any chosen one of the playing spaces pendently when the curtain-like game 60 board is sustained in a pendent position.

11. A game board of curtain-like construction capable of being rolled up, in combination with a spring roller to which one edge of the game board is made fast, and a 65 casing in which the roller is mounted, said casing having one side constructed to open to permit the withdrawal of the game board from the casing into visible position.

12. A game board of curtain-like construction capable of being rolled up, in combination with a spring roller to which one edge of the game board is made fast, and a 70 casing in which the roller is mounted, said casing having one side constructed to open 75 to permit the withdrawal of the game board from the casing into visible position, said casing having sustaining means at a point remote from the side adapted to open to permit the game board to be withdrawn from 80 the casing to pendent position with that side of the casing adapted to open to the rear of the game board.

13. A game board of curtain-like form capable of being rolled up with sustaining 85 means constructed to permit the rolling up or spreading out of the game board, the latter having playing spaces produced thereon and storage spaces outside of the area devoted to the playing spaces, and playing devices adapted to the game board, said devices, the playing spaces and the storage spaces being provided with coacting sustaining 90 means for the playing devices.

14. A means for playing games comprising 95 a curtain-like game board of magnified or exaggerated size and adapted to be hung in pendent position, and playing devices of corresponding magnified or exaggerated size adapted to the game board, said playing 100 devices and game board having coacting means for sustaining the playing devices on the board, and manipulating means for the playing devices constructed to engage playing devices otherwise out of reach of the 105 players.

In testimony that I claim the foregoing as my own, I have hereto affixed my signature in the presence of two witnesses.

GEORGE WILLIAM COOPER.
